UNITED STATES PATENT OFFICE

FRANK G. BUTLER, OF FARGO, NORTH DAKOTA

DOOR OPERATING AND LOCKING MECHANISM

Application filed September 13, 1929. Serial No. 392,352.

My invention relates to door operating means particularly adapted for the operation of garage doors where it is desired to provide means for opening the doors readily either from the inside or the outside of the door and to hold and support the doors against moving shut while driving into the garage.

A feature of the invention resides in a simple inexpensive structure which is applicable to garage doors designed with means which may be operated from the outside by the pulling of the operating cord to either open or close the same, the operating cord being adapted to lift the door opening and closing mechanism out of a latched position so that the doors may be operated, and suitable brace arms being provided which hold the doors braced open and equally hold the doors braced in closed position.

It is also a feature of my invention to provide means for electrically releasing the catch means so that the doors may be operated when the electrical means is operated by suitable switch means to permit the doors to be operated to open the same from the outside. By this means the autoist may drive up to his garage and unlock and operate the switch with a key and then by suitable hand operated ropes or cables operate the doors to open the same and drive into the garage without getting out of the automobile.

These features together with other details and objects of my invention will be more clearly and fully set forth in the specification and claims.

In the drawings I have illustrated a perspective view in Figure 1 which illustrates a portion of a garage and which shows the operating cables or ropes in operating position.

Figure 2 illustrates a diagrammatic detail of my door operating mechanism, looking up toward the ceiling of the garage.

Figure 3 illustrates a detail of a portion of my door operating mechanism.

Figure 4 illustrates a detail of the electrical releasing means.

Figure 5 diagrammatically illustrates a detail of a garage showing another form of

my door operating mechanism, looking up toward the ceiling.

Figure 6 is a perspective detail looking upwardly toward the ceiling in the garage employing my door operating mechanism. 55

Figure 7 is a perspective detail of one of the doors, showing the locking means for the same.

Figure 8 diagrammatically illustrates a portion of the locking mechanism for the doors illustrated in Figure 7, showing a section near the bottom of the doors. 60

Figure 9 illustrates diagrammatically the relative position of the doors at the top showing the locking means illustrated in 65 Figure 7.

My door operating mechanism A is designed to be supported on the ceiling of the garage as illustrated in Figures 2, 5 and 6, and is provided with an operating and controlling beam 10 which is slidably supported in the brackets 11 to the ceiling or in the top of the garage in a manner so that in the operation of the beam 10 the doors 12 of the garage may be operated to open or close the 75 same. 70

The operating or control beam 10 is connected by the brace members 13 to the respective doors 12 by hinges 14. In the structure illustrated in Figure 5 and also Figure 80 6 the doors 12 are connected to the controlling beam 10 by the rods 15. These rods 15 are connected on one end by a cross member 16 to the controlling beam 10 while the other end is pivotally connected in the eye members 85 16' to the doors. The controlling beam 10 is formed with a shoulder member 18 as illustrated in Figure 2 which engages with the inner bracket 11 as illustrated in the drawings when the control beam 10 is set to hold 90 the doors 12 locked in closed position. The beam 10 carries a cam lifting member 20 which is pivoted at 21 in the control beam 10 and by means of an operating rod 22 which extends through the guiding bracket 23 95 the rod 22 is held slideable so that it can be moved to operate the cam 20. The cam 20 is positioned in a center slot 24 in the operating beam 10 and its operating end 25 is normally held away from the inner surface of the 100

bracket 11 by the coil spring 26 which normally holds the parts in the position illustrated in Figure 3. When the operating rope or cable 27 which is connected to the front end of the rod 22 is pulled, the cam 20 will be operated to lift the control bar 10 sufficiently to permit the latch shoulder 18 to clear the inner surface of the bracket 11 and the continued pull on the cable 27 will pull the operating and controlling beam 10 forward toward the doors 12. The beam 10 when released from the position just described may be operated readily by the cable 27 to force the bracket arms 13 against the doors 12 to open the same very easily. This is accomplished more readily for the reason that the arms 13 have the ends which are hingedly connected to the doors 12 positioned closely adjacent the center point between the doors or closely adjacent the operating control beam 10. Thus a strong leverage is directed against the doors to open them and they may also be pushed by the front end 28 of the control beam 10.

The cable 27 runs along longitudinally of the control beam 10 to the pulley 29 positioned near the doors 12 and from the pulley 29 runs over to the pulley 30 and down to the weight 31 then up to the pulley 32 and on out of the garage to the anchoring point 33, as illustrated in Figure 1, adjacent the drive to the garage.

The control beam 10 is also provided with a latch lug 35 and an operating cam 36, the cam 36 being similar in function to the cam 20 and positioned in the beam in a similar manner ahead of the cam 20 in the slot 37. When the cable 27 is operated to cause the control beam 10 to be lifted in a manner to release the catch lug 18 from the bracket 11 and the continued pull of the cable operates to open the doors 12, the catch lug 35 slips through the forward bracket 11, which is positioned adjacent the doors 12, and the catch lug 35 engages on the other side of this bracket 11 to hold the doors in open position. The weight of the control beam 10 is sufficient to cause it to drop into locking position by gravity.

When it is desired to close the doors from the open position illustrated in dotted outline in Figures 2 and 5, the cable 38 is engaged and this cable operates the cam 36 against the action of the spring 39 which normally holds the cam the same as the spring 26 and thus elevates the control beam 10 to permit the latch lug 35 to lift out of engagement with the front bracket 11 and the continued pulling of the cable 38 draws the control beam 10 into inward position within the garage and simultaneously closes the doors 12. Thus the latch lug 18 on the beam 10 holds the doors in closed position when engaging with the inner bracket 11 and when the latch lug 35 is moved to engage with

the front bracket 11, the doors are held in locked open position.

The operating cable 38 extends along to the outside of the garage virtually parallel with the cable 27 and to open the doors the cable 27 is engaged and to close them the cable 38 is engaged. The cable 38 extends from the pulley 40 which carries a portion of the cable 38 from the cam 36 along in line with the control beam 10 and then over to the pulley 41 and down to the weight 42 and up to the pulley 43 and from there out to the point of anchoring 33. The cable 38 may also be held from a beam depending adjacent the free end of the cable 27.

The control beam 10 slides back and forth in the brackets 11 and the latch lugs 18 and 35 hold the same against longitudinal movement in the respective positions described. It is therefore apparent that the garage doors 12 may be easily opened by my door operating mechanism.

I provide a means of locking the control beam 10 against movement by an electrically controlled latch dog 44 which is pivoted at 46 on the bracket 23 and the free end 45 of which engages in a suitable notch in the rod 22 as illustrated in Figure 4. By means of suitable electric wires running from the solenoid 47 which is adapted to lift the latch 44 out of engagement with the rod 22, and a suitable source of electric energy not illustrated, nor is the particular wiring illustrated as this is of ordinary construction, the operation of the control beam 10 to open the doors 12 may be controlled electrically. I provide a standard 48 outside of the garage which projects upward and in which a suitable lock 49 is provided in the top of the standard which is adapted to be operated by a suitable key. The operation of the lock by the correct key will operate the solenoid 47 to lift the latch 44 and thus permit the operation of opening the doors 12 by pulling on the cable 27. This provides an electric locking means which prevents the doors 12 from being opened until they are released by means of a key in the lock 49 and thus I provide a very simple and yet effective electrical locking means for my door operating mechanism.

I also provide an automatically operated lock catch in the form of a rod 50 which may be attached to one or both of the doors 12 and which extends and is pivotally supported through the brackets 51 as illustrated in Figure 7. The rod 50 is bent on its end to provide an upper lug portion 52 which engages against a pin 53 positioned at the top of the door so that as the doors are brought toward closed position the lug 52 will act as a cam in engagement with the pin 53 to turn the rod 50. The lower end of the rod is formed with a hook 54 which is adapted to engage over the pin 55 in the operation or rotation of the rod 50 and thus draw the lower part of the door or doors 12 into tight closed po-

sition. With this mechanism and my easy simple means of operating garage doors, I provide an economical structure for autoists with which they may equip their garage to provide a very simple and effective door operating and locking mechanism having all of the advantages of holding the doors firmly locked closed and rigidly locked open, so that the doors cannot blow shut or come against the car while driving in or out of the garage.

5 10 My garage doors 12 may be operated from the inside of the garage to close or open the same by pulling upon the weighted members 31 or 42 respectively, the weighted members 15 acting as handles in conjunction with the cables 27 and 38.

In accordance with the patent statutes I have described the principles of my door operating and locking mechanism and while I have endeavored to represent the best embodiment thereof to set forth the uses of the same, I desire to have it understood that the drawings are only suggestive of a means of carrying out the invention and that features and details may be applied or varied 20 within the scope of the following claims without departing from the spirit of my invention.

I claim:

30 1. A door operating and locking mechanism including, a controlling beam member, means for supporting said beam slidably longitudinally thereof, connecting arms adapted to connect said beam with the doors, catch means for holding said beam against longitudinal movement, means for lifting said beam into releasing position and simultaneously operating said beam to open or close the doors.

40 2. A door operating and locking mechanism comprising, a longitudinally operating beam member slidable through bearings, catch means for holding said member against longitudinal movement, releasing means for moving said beam member to release the same, doors, arms for connecting said doors to said operating member, means for operating said releasing means to release said operating member and permit the same to slide longitudinally to open or close said doors.

45 3. A garage door operating means including, arms connected to said doors, a slidable member connecting with said arms, catch means for holding said slidable member locked in closed position, and catch means for holding said slidable member in open position, means for lifting said slidable member out of engagement with said catches and cable members connected to and operating said lifting means extending to the outside of the garage from said catch means whereby the engagement of said cable means permits the operator to open or close said doors by pulling on said cables.

50 4. A garage door operating mechanism in-

cluding door brace members hingedly connected thereto, a longitudinally slidable and vertically movable unitary latching and operating member to which said brace members are hingedly connected, catch means co-operable with said latch, cable means for operating said latch member in a manner to automatically lock said doors open or closed, when this position of the door is reached by pulling on said cable members.

5 70 15 20 25 30 35 40 45 50 55 60 65 70 75 80 85 90 95 100 105 110 115 120 125 130 A door operating mechanism including, doors hingedly supported in a manner to swing open and shut, brace members connected to the free ends of said doors, a slideable latch member, bearings through which said latch members may slide, means for connecting said brace members to said latch member, means for locking said latch member by gravity, cam means for lifting said latch member to unlock the same, and cable means connected to said cam means to operate said latch and to operate said doors.

6 6. A door operating mechanism for a garage and the like including, a series of doors adapted to swing open and shut, a slideable latching member, brace members pivotally connected to said latching member and the free ends of said doors, cam means for operating said latching member to unlatch said latching member, and cable means connected to and operating said cam means and to simultaneously operate said doors into open or closed position.

7 7. A door operating mechanism including, a series of doors, a latch means for holding said doors in open or closed position, said latch means having brace arms connecting with said doors, means for releasing said latch, and electrical means for unlocking said releasing means for said latch means to permit the same to be operated to open said doors.

8 8. A garage door operating mechanism including, a latch member, cable operating means, brace members connecting said latch member to a pair of doors, at catch co-operable with said latch, means operable by said cable to disconnect said latch from said catch, electrical means for locking said latch means against operation, and means for operating said latch means when said electrical means has unlocked the same by said cable members which may be pulled to open or close said doors.

FRANK G. BUTLER. 120
